UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

FEEDER FOR INGOT MOLDS.

Application filed February 9, 1924. Serial No. 691,738.

To all whom it may concern:

Be it known that BLOOMFIELD H. HOWARD and ERNEST J. TURNER, citizens of the United States, residing, respectively, at Washington, District of Columbia, and Pittsburgh, in the county of Allegheny and State of Pennsylvania, have invented certain new and useful Improvements in Feeders for Ingot Molds, of which the following is a specification.

Our invention relates to improvements in feeders for ingot molds.

The object of our invention is to provide a feeder for ingot molds adapted to be supported on the upper end of the mold and also provide a feeder which will prevent the formation of what is known as "piping" and at the same time reduce segregation.

Another object of our invention is to provide a feeder having a large number of curved walls adapted to correspond with the walls of the mold whereby any imperfections in the wall of the ingot is more readily rolled out during the rolling process and which also enables the scale on the outer periphery of the ingot to more readily peel off of the ingot during the rolling process, and thus produce a more perfect finished article.

A further object of our invention is to provide a feeder of this character which can be readily and cheaply made by dies and a supporting means formed as an integral part thereof and serving as means for strengthening that portion of the feeder above the mold and is an improvement over Figure 1 of Patent No. 1,481,205 dated January 15, 1924, which figure was incidentally shown but for which no claim was made.

In the accompanying drawings:—

Figure 1 is a perspective view of an ingot mold showing our improved feeder applied thereto.

Figure 2 is a vertical transverse sectional view of Figure 1.

Figure 3 is an enlarged top plan view partly broken away.

Figure 4 is a top plan view of a modified form of feeder.

Figure 5 is a vertical transverse sectional view of Figure 4.

Figure 6 is a top plan view of a still further modified form of feeder, showing the

supporting ribs arranged so that the feeder can be reversed in the mold.

Figure 7 is a vertical transverse sectional view of Figure 6.

Figure 8 is a top plan view of a still further modified form of feeder.

Figure 9 is a top plan view of Figure 1 showing straight interior walls.

Figure 10 is a top plan view of Figure 4 showing straight interior walls with slightly rounded corners.

Figure 11 is a top plan view of Figure 6 showing straight interior walls with slightly rounded corners.

Figure 12 is a top plan view of Figure 8 showing straight interior walls with slightly rounded corners.

Referring now to the drawings, 1 represents the ingot mold and 2 the feeder. The feeder as shown in Figure 1 of the drawings is of a rectangular form and having four walls bellied inwardly as indicated at 3, 4, 5 and 6 which are oppositely arranged and connected by the four short corner walls 7, 8, 9 and 10 which as shown in Figure 3 are of a modified form. Carried by the outer periphery of the feeder are the vertically disposed semi-circular supporting ribs 11 which terminate a considerable distance from the lower end of the feeder to allow a portion thereof to enter the feeder as clearly shown in Figure 2 of the drawings. We have shown the outer faces of the walls 3, 4, 5 and 6 concave. This is done so the outer walls of the feeder will conform to the inner walls of the mold and will save material in the manufacture of the feeder. It will also be understood that the inner walls of the feeder could be straight or of any other contour without departing from our invention.

In Figures 4 and 5 we have shown a rectangular feeder having the four bellied walls 12, 13, 14 and 15 oppositely arranged and connected by the four straight walls 16, 17, 18 and 19. In this form the supporting ribs 20 are arranged on the outer periphery in the same relative position as that shown in Figures 1, 2 and 3 for supporting the feeder on the mold with a portion thereof extending into the mold as shown in Figure 5.

In Figure 6 we have shown a mold having the four bellied walls 21, 22, 23 and 24 op-

positely arranged. The bellied walls 22 and 24 have ends terminating in the curved walls 25, 26, 27 and 28 and connecting these curved walls 25, 26, 27 and 28 with the walls 21 and 23 are the straight walls 29, 30, 31 and 32. In this form shown in Figure 6 the supporting ribs 33 are arranged intermediate the ends of the feeder and nearer one end than the other so that the feeder can be reversed to allow the feeder to extend a greater or less distance into the bore of the mold. The upper and lower edges of the feeder are beveled as indicated at 34 and 35.

In the modification shown in Figure 8 the four walls 37, 38, 39 and 40 are bellied to a greater extent than that shown in the other figures and are connected by the straight walls 41, 42, 43 and 44 oppositely arranged. In this form a supporting rib 45 is shown carried by the outer face of each of the bellied walls and also each of the straight walls.

In Figures 9, 10, 11 and 12 as heretofore stated we have shown the forms of feeder shown in Figures 1, 4, 6 and 8 in which the interior walls are straight with slightly rounded corners in which like reference numerals indicate like parts.

Having thus fully described our invention what we claim is:—

1. A feeder for ingot molds comprising four inwardly curved walls connected by four walls of a different contour.
2. A feeder for ingot molds comprising a body portion having inwardly bellied, oppositely arranged walls, connected by shorter oppositely arranged walls and supporting ribs carried by the outer face of said wall.
3. A feeder for ingot molds comprising a body portion having inwardly bellied walls

oppositely arranged and supporting means carried by the outer face of the body portion.

4. A feeder for ingot molds comprising a body portion having inwardly bellied, oppositely arranged walls connected by inwardly curved walls. 45

5. A feeder for ingot molds comprising a body portion having inwardly bellied, oppositely arranged walls and supporting ribs 50 carried by the outer periphery of the body portion.

6. A feeder for ingot molds comprising a body portion having four oppositely arranged, inwardly bellied walls connected by 55 four oppositely arranged short walls.

7. A feeder for ingot molds comprising a body portion having four inwardly bellied oppositely arranged walls connected by four oppositely arranged walls of a different 60 contour.

8. A feeder for ingot molds comprising four inwardly bellied oppositely arranged walls connected by oppositely arranged walls of different contours and supporting ribs semi-circular in cross section carried by the outer face of the wall.

9. A feeder for ingot molds comprising a body portion having inwardly bellied outer faces and straight inner faces. 70

10. A feeder for ingot molds comprising a body portion having inwardly bellied outer faces oppositely arranged and connected by shorter outer bellied faces and straight inner faces slightly rounded at the 75 corners.

In testimony whereof we affix our signatures.

BLOOMFIELD H. HOWARD.
ERNEST J. TURNER.
